UNITED STATES PATENT OFFICE.

ERNEST LINCOLN SAGE, OF NEWTON CENTER, MASSACHUSETTS, ASSIGNOR, BY MESNE ASSIGNMENTS, TO EASTERN FOUNTAIN COMPANY, A CORPORATION OF MASSACHUSETTS.

FLUID PRESSURE OR FLOW REGULATOR OR CONTROLLER.

1,136,619.

Specification of Letters Patent. Patented Apr. 20, 1915.

Application filed January 17, 1911. Serial No. 603,061.

To all whom it may concern:

Be it known that I, ERNEST LINCOLN SAGE, a citizen of the United States, and resident of Newton Center, in the county of Middlesex 5 and State of Massachusetts, have invented an Improvement in Fluid Pressure or Flow Regulators or Controllers, of which the following description, in connection with the accompanying drawings, is a specification, 10 like letters on the drawings representing like parts.

The invention hereinafter to be described relates to fluid pressure or flow regulators or controllers, and has for its object and aim to 15 provide a device of the general character referred to of improved construction and efficient in operation, all of which will best be understood from the following description, taken in connection with the accompanying 20 drawings, of one form or embodiment of means for carrying the invention into practical effect, while the scope of the invention will be more particularly pointed out in the appended claims.

25 In the drawings: Figure 1 is a sectional elevation of a preferred form of regulator embodying my invention; Fig. 2 is a plan view thereof; Fig. 3 is a central longitudinal section in a plane perpendicular to the plane 30 of the latter figure, with the parts in the same position as in the latter figure; Fig. 4 is a central longitudinal section similar to Fig. 3, but with the parts in different position; Fig. 5 is a cross section on line 5—5 of 35 Fig. 4, and Fig. 6 is a cross section on line 6—6 of Fig. 4.

Similar reference numerals indicate corresponding parts in all of the figures of the drawings.

40 In the preferred embodiment of my invention selected for illustrative purposes, the operative parts are contained in a preferably cylindrical tubular casing 2 provided internally with an annular shoulder 4. Referring to Fig. 1, there is slidably mounted in the casing 2, below the shoulder 4, a member 6, bored axially at 8, as shown in Figs. 3, 4 and 6, from its lower end but closed at the upper end where it terminates in a solid 45 spindle 10. The member 6 telescopes in a sleeve-like member 12 having, at its upper end, an exterior collar or shoulder 14, and it and the member 6 are surrounded by a helical 50 spring 16, bearing at one end upon said col-

lar 14 of the sleeve 12 and at its other end 55 upon a collar 18 provided upon the member 6 near the lower or outer end of the latter. The upper end of the spindle 10 extends into the lower end of a sleeve-like member 20, similar to the sleeve 12, slidably mounted 60 in the casing 2 above the annular collar 4, and is there pivoted to a pin 22 extending across the bore of the sleeve 20 and having its ends fixed in the walls of the latter, as shown in Figs. 3 and 4. The sleeve 20 slid- 65 ingly surrounds a member 24, provided with an axial bore 26, open at its upper or outer end and closed at its lower or inner end, as shown in Figs. 3 and 4. The sleeve 20 and the member 24 are surrounded by a helical 70 spring 28, bearing at one end upon a collar 30 provided on the upper or outer end of the member 24 and at the other end upon a collar 32 provided on the lower or inner end of the sleeve 20. The spring 28 tends to sepa- 75 rate the sleeve 20 and member 24, such action of said spring being limited by contact of the collar 32 of the sleeve 20 with the annular shoulder 4 of the casing 2 and of the collar 30 of the member 24 with a suitable 80 abutment, such as a foraminous disk 34, having its edge screw-threaded, and being screwed into the interiorly screw-threaded upper or outer end of the casing 2, Figs. 1 and 3. Similarly, the spring 16 tends to 85 separate the member 6 and sleeve 12, such action of said spring being limited by contact of the collar 32 of the sleeve 20 and the collar 14 of the sleeve 12 respectively with opposite sides of the annular shoulder 4 on 90 the inside of the casing 2.

It will be readily seen that with the construction so far described, and nothing more, very little if any fluid entering at the end E of the apparatus would pass through it, 95 as for all practical purposes, and particularly in the case of liquids, the collars 18, 14, 32 and 30, may be considered to be a close fit in the casing 2, the amount that might pass around said collars being negligible as 100 regards the effect that it might have upon the object that it is sought to obtain by the present invention. Accordingly the invention contemplates the provision of openings for the passage of fluid, and which will co- 105 operate with the parts so far described or their equivalents, to enable the pressure of the fluid to be controlled or regulated, as

will hereinafter be more particularly described.

The embodiment of the invention herein described and illustrated in the drawings as one means for carrying the invention into practical effect is intended more particularly for controlling or regulating water pressure, and the system of openings used in said embodiment of the invention has proven itself in practice to be eminently suited to the purpose which it has been sought to attain, but it will be understood that the invention is not limited to the specific openings referred to and which will now be described, either as regards their nature or number or location, nor in any other manner whatsoever.

The collars 18, 32 and 30 on the members 6, 20 and 24 respectively are each provided with three grooves or slots extending longitudinally thereof and herein designated by the reference numerals 36, 38 and 40 respectively, the slots upon each collar being preferably disposed at substantially equal distances from each other. Only two of these slots are illustrated in the case of the collars 18 and 32, while all three of those on the collar 20 are illustrated in Fig. 2. The member 12 is provided with two openings 30 in the form of two longitudinally extended slots or slits 42, 42 upon opposite sides thereof, extending from a point near its lower end up a short distance into the collar 14. Each of the members 6, 20 and 24 is provided with two openings in the form of two transverse slots 44, 44, 46, 46, and 48, 48 upon opposite sides of said members respectively.

The device is provided at either end with 40 interiorly screw-threaded portions 50, 52 to enable it to be connected to or inserted in the apparatus in which it is to be used, it being understood that the fluid, the pressure of which is to be controlled or regulated, 45 must enter the device by the end E and leave it by the end D.

The operation of the device will now be described.

With the parts in the position shown in 50 Figs. 1 and 3, the fluid, in the illustrated example water, enters the casing 2 at the end E and flows through the three slots 36 of the collar 18 into the space between the collar 18 and the collar 14 on the member 12. 55 The water also flows into the axial bore 8 of the member 6 and out, into the space between the two collars 18 and 14, through the slots 44, 44 provided in the member 6, said slots being below the lower end of the 60 sleeve member 12, when the parts are in this position. From the space between the collars 18 and 14 the water flows through the longitudinal slots 42 of the sleeve member 12 into that part of the bore of the latter 65 situated above the closed inner end of the

member 6, where it flows up around the spindle 10 and out of the upper end of the sleeve member 12 into the space between the collars 14 and 32 on the sleeve members 12 and 20 respectively. From this space the 70 water flows on the one hand through the slots 38 of said collar 32 and on the other hand through that portion of the bore of the sleeve member 20 below the closed inner end of the member 24 and through the slots 75 46 of said sleeve member 20, into the space between the collars 32 and 30 of the sleeve member 20 and member 24 respectively. From this space the water flows through the slots 40 of the collar 30 and through the 80 slots 48 of the member 24 and the bore 26 of the latter out of the device through the openings in the foraminous disk 34. If the pressure of the water entering the device increases, the increased pressure acting on the 85 collar 18 will move the member 6 upwardly and with it the sleeve 20, said parts, it will be remembered, being connected by the spindle 10 of the member 6 and the pivot pin 22. The portion of the member 6 bearing the 90 slots 44 is thus caused to enter the sleeve 12 and the sleeve 20 is caused to slide up over the slots 48 in the member 24, while the closed inner end of said member now extends below the slots 46 in the sleeve 20, 95 this movement of the member 6 and sleeve 20 taking place against the pressure of the springs 16 and 28. The slots 44 in the member 6, the slots 48 in the member 24 and the slots 46 in the sleeve 20 now being closed, 100 water can enter the space between the two collars 18 and 14 only through the slots 36 in the collar 18, except what little may pass through the small coincident portions of the slots 44 and 42. Furthermore, owing to the 105 closure of the slots 46 and 48 of the sleeve 20 and member 24 respectively, water can now only enter the space between the collars 32 and 30 through the slots 38 of said collar 32 and leave said space and the device by the slots 40 in the collar 30. It will 110 therefore be seen that as the pressure of the water below the device increases the volume of water that can leave the device is decreased. Furthermore it will be noted that 115 all the water that passes through the device must flow through the slots 42 in the sleeve 12 and that as the pressure of the water entering the device increases, thus forcing the closed end of the member 6 farther and farther up into the bore of the sleeve 12, the effective length of said slots 42 is shortened 120 more and more so that less and less water passes through the device, until, should the pressure of the water entering the device increase that much, only that portion of the slots 42 contained in the collar 14 remains 125 free for the passage of water, as shown in Fig. 4, closure of that portion of said slots being prevented by contact of a shoulder 130 54

provided on the collar 18 with the lower end of the sleeve 12. As the pressure diminishes the parts, under the action of the springs 16 and 28, will regain their initial positions, 5 it being clear that, as the flow of water from the device gradually decreased in proportion as the pressure of the water entering the device increased, so now the flow of water from the device will gradually increase 10 in proportion as the pressure of the water entering the device decreases. It will therefore be seen that with the aid of a regulator embodying the present invention the pressure of a fluid on leaving the regulator will 15 remain for all practical purposes the same though the pressure of the fluid entering the regulator vary. So true is this that a jet or bubble of water issuing from a pipe connected to the upper end of a regulator 20 embodying this invention retained substantially the same height, although the pressure of the water entering the regulator varied between considerable limits, rapid variation 25 between 15 to 140 pounds pressure being noted in the water entering the device without producing any perceptible variation in the height of the jet or bubble of water at the exit thereof. By using springs of variable strength, the device can be rendered 30 more or less sensitive, as will be readily understood.

For facilitating the assembling of the device the collar 18 is preferably removable, it being held in place upon the outer end of 35 the member 6 against a shoulder 56 (see Fig. 3) upon the latter, by a bored nut 58 having screw-threaded connection with the outer end of said member.

By using slots 36, 38 and 40 provided as 40 described in the peripheral surface of the collars 18, 32 and 30 respectively as openings for the passage of the water instead of ordinary perforations, foreign matter held in suspension in the water flowing through the 45 apparatus is not so likely to become lodged in said openings, and the movement of the collars in the operation of the device tends to dislodge any foreign matter from said openings.

50 Obviously many changes may be made in the details of construction without departing from the true spirit of the present invention, which is definitely set forth in the claims.

55 What is claimed is:

1. A fluid pressure or flow regulator comprising a casing having open ends to permit the flow of fluid therethrough, a plurality of telescoping tubular members in 60 said casing having lateral openings in the walls thereof, partitions in said casing and members to cause fluid flowing through said casing to pass alternately inwardly and outwardly through the lateral openings in 65 the several members, said members being

movable to telescoped position to close said lateral openings by the pressure of said fluid, and springs for distending said members.

2. In a fluid pressure or flow regulator, 70 the combination with a casing having open ends to permit the flow of fluid therethrough, of means within said casing for dividing said flow into a plurality of portions and including means for completely 75 cutting off a portion of said flow at one point, means for subsequently varying the amount of the remaining portion of said flow, and means controlled by the pressure of said fluid and located at another point in 80 the path of said flow for controlling said two last named means.

3. A fluid pressure or flow regulator comprising a casing having open ends to permit the flow of fluid therethrough, and 85 means within said casing for dividing said flow into a plurality of portions, said means including a plurality of members having openings through which said fluid passes, said members being movable by the pressure of said fluid to close all the openings in one of said members completely and to vary 90 the size of the openings in another of said members.

4. A fluid pressure or flow regulator comprising a casing having open ends to permit the flow of fluid therethrough, a plurality of telescoping tubular members within said casing having lateral openings in the walls thereof, partitions in said casing 100 and members to cause a portion of the fluid flowing through said casing to pass alternately inwardly and outwardly through said openings, and yielding means for normally distending said members, said members 105 being movable by the pressure of said fluid to telescoped position to close the openings in one of said members completely and to vary the effective size of the openings in another of said members.

5. A fluid pressure or flow regulator comprising a casing having open ends to permit the flow of fluid therethrough, a plurality of telescoping tubular members within said casing, one of said members having in its 115 wall one or more transversely arranged slots and the other of said members having in its wall one or more longitudinally arranged slots, and yielding means for normally distending said members, said members being 120 movable by the pressure of said fluid to telescoped position to close said transversely arranged slots completely and to vary the effective length of said longitudinally arranged slots.

6. A fluid pressure or flow regulator comprising a casing having open ends to permit the flow of fluid therethrough, a plurality of telescoping tubular members within said 130 casing, one of said members having in its

wall one or more transversely arranged slots and the other of said members having in its wall one or more longitudinally arranged slots, partitions in said casing and members 5 to cause a portion of the fluid flowing through said casing to pass alternately inwardly and outwardly through said slots, and a spring for normally distending said members, said members being movable by 10 the pressure of said fluid to telescoped position to close said transversely arranged slots completely and to vary the effective length of said longitudinally arranged slots.

7. A fluid pressure or flow regulator comprising a casing having open ends to permit the flow of fluid therethrough, means within said casing controlled by the pressure of said fluid, and means operated by said first named means for completely cutting off a 15 portion of said flow beyond said first named means in the direction of said flow and for governing said flow at a point intermediate said first named means and said point of cut off.

25 8. A fluid pressure or flow regulator comprising a casing having open ends to permit the flow of fluid therethrough, means within said casing controlled by the pressure of said fluid, and means operated by 30 said first named means and located beyond the same in the direction of the flow of said fluid through said casing for completely cutting off a portion of said flow at one point and for subsequently varying the

amount of the remaining portion thereof at 35 another point.

9. A fluid pressure or flow regulator comprising a casing having open ends to permit the flow of fluid therethrough, means within said casing controlled by the pressure of said fluid, and means operated by 40 said first named means for governing said flow at a point adjacent said first named means and for further governing said flow at a point beyond said first named means in 45 the direction of flow, said last named means comprising means for completely cutting off a portion of said flow at one of said points.

10. A fluid pressure or flow regulator comprising a casing having open ends to 50 permit the flow of fluid therethrough, means within said casing controlled by the pressure of said fluid, and means operated by said first named means for completely cutting off a portion of the flow of said fluid 55 through said casing at a point adjacent said first named means and for further completely cutting off another portion of said flow at a point beyond said first named means in the direction of said flow. 60

In testimony whereof, I have signed my name to this specification, in the presence of two subscribing witnesses.
